UNITED STATES PATENT OFFICE

171,199

HOUSING FOR ORGANIC WASTE TREATMENT APPARATUS

Myles W. Edwards, Reading, Pa., assignor to
Wertz Engineering Co., Inc., Reading, Pa., a
corporation of Pennsylvania

Application June 6, 1952, Serial No. 20,061

Term of patent 14 years

(Cl. D55—1)

To all whom it may concern:

Be it known that I, Myles W. Edwards, a citizen of the United States of America, residing at Eisenbrown Road, Riverview Park, Reading, in the county of Berks and State of Pennsylvania, have invented a new, original, and ornamental Design for a Housing for Organic Waste Treatment Apparatus, of which the following is a specification, reference being had to the accompanying drawing forming part thereof.

Figure 1 is a front perspective view of the housing for organic waste treatment apparatus embodying my new design, and

Fig. 2 is a rear perspective view thereof.

I claim:

The ornamental design for a housing for organic waste treatment apparatus, as shown.

MYLES W. EDWARDS.
